United States Patent Office.

EDMUND D. CROSLEY, OF SCOTT, NEW YORK.

Letters Patent No. 61,609, dated January 29, 1867.

IMPROVED WASHING MACHINE.

The Schedule referred to in these Letters Patent and making part of the same.

TO ALL WHOM IT MAY CONCERN:

Be it known that I, EDMUND D. CROSLEY, of Scott, in the county of Cortland, and State of New York, have invented a new and useful Improvement in Washing Machines; and I do hereby declare that the following is a full, clear, and exact description of the construction and operation of the same, reference being had to the annexed drawings, making a part of this specification, in which a perspective view of the improvement is represented.

a a represent the box or receptacle in which the material to be washed is placed, and made slightly oblong and flaring at the sides. This box has a concave bottom, and the sides *g g* are ribbed laterally. Across the top of the box, from end to end, is a support or bar *d*, from which are suspended the beaters *b b*. These beaters are much the broadest at the bottom, their ends smooth and vertical, but their sides ribbed horizontally and converging or wedge-shaped, and swinging loosely on the bar *d*, from side to side of the box. From the upper ends of the handles of these beaters, crank-rods *e e* connect with the crank *i* upon opposite sides, which is driven by cogged wheels *j k*. On turning the handle or crank *u*, the beaters move in opposite directions, one beating the cloth and falling back as the other comes forward. The sides of the box being ribbed, and the beater being broadest at the bottom, and swinging from the bar *d* as a centre, the cloth is given an upward motion as the beater swings up to the side of the box, and as it falls back, the cloth being bunched and inclining upon the beater, follows it; and also, the cloth, being pressed in the form of a wedge, the heaviest part uppermost, falls over as the beater recedes, or rolls partly over toward the centre of the box, and as the same process is being constantly repeated, the cloth is kept rolling over and over as it is beaten.

I claim the combination of the beaters *m m*, when pivoted upon the central bar and connected to the pitman cranks by the jointed arms *e e*, all as described, and for the purpose set forth.

EDMUND D. CROSLEY.
